DESIGN FOR A STOVE.

Design No. 12,614, dated December 20, 1881.

Cut 273.

UNITED STATES PATENT OFFICE.

H. CLAY BASCOM AND FRANCIS RITCHIE, OF TROY, NEW YORK, ASSIGNEES
TO N. S. VEDDER PATTERN WORKS, BASCOM, GALBRAITH & CO., OF
SAME PLACE.

DESIGN FOR A STOVE.

SPECIFICATION forming part of Design No. 12,614, dated December 20, 1881.

Application filed November 16, 1881. Term of patent 7 years.

To all whom it may concern:

Be it known that we, H. CLAY BASCOM and FRANCIS RITCHIE, each a citizen of the United States, residing in the city of Troy, in the county of Rensselaer and State of New York, have jointly invented and produced a new and original Design for Stoves, of which the following is a specification, reference being had to the accompanying cut, print, or engraving of a stove embodying said design.

One feature of this invention is the design for the cap portion, the same being composed of the coniform plate B, the urn C upon said plate, and the two lateral wings D D, conforming to and extending along and across opposite sides of the surfaces of said plate and urn, said plate, wings, and urn being shaped, arranged, and combined so as to present substantially the appearance represented in the aforesaid cut, irrespective of the ornamental figures upon the urn, wing, and plate.

A further part is the design for each wing D, consisting of the inner border, a, outer projecting top and bottom scroll-bands, b b', intervening inwardly-curved scroll-bands, c c', bordered, one inwardly by the scallop-edging c² and both outwardly by the downwardly-flaring and terminally-pointed ornamentation d, and inclosing the spreading ornaments e e' on the upper and lower face parts of the plate, all of said parts being shaped and combined substantially as shown in the aforesaid print.

The design for the upper front plate consists, essentially, of the raised rectangular panel E, having convexly-curved edges, the border ornamentations f, and the compound middle ornament, consisting of the central ornamented square, g, with its angles directed toward the sides of the panel, the pairs of compound ten-drill-form and flaring ornaments h and h', extending from the angles of the central square, and the intermediate ornaments, i, extending from the sides of said square, and all shaped and arranged together substantially as shown in the aforesaid engraving.

The design for the lower front door consists of the upper panel, F, curved convexly up-

ward, and formed with the series of mica lights j, having rectangular bottom and reversely-curved arched tops, with the intermediate leaf ornaments, k, and lateral ornaments l, in combination with the lower panel, G, curved concavely downward and forward, and formed with the series of draft-apertures m, having rectangular lower parts and reversely-curved tops, with the intermediate ornaments, n, and top border ornamentation, o, all shaped and arranged substantially as represented in the accompanying cut.

The design for the legs consists of the upper bent band portion, H, having thereon the series of round top ornamented arches p and ovoloshaped ends, in combination with the lower swelling portion, I, having thereon the upwardly-flaring fan form ornament q, all shaped and disposed as represented in the accompanying print.

What we claim as our invention is—

1. The design for the cap portion, composed of the coniform plate B, urn C on said plate, and lateral wings D D, conforming to and extending across opposite sides of said plate and urn, as set forth.
2. The design for the wings D, consisting of the ornamental parts a b b' c c' c² d e e', all shaped and arranged together as set forth.
3. The design for the upper front plate, composed of the parts E f g h h' i, all shaped and arranged together as set forth.

4. The design for the lower front door, consisting of the parts F j k l and G m n o, all shaped and arranged together as set forth.

5. The design for the legs, consisting of the parts H p and I q, shaped and arranged together as set forth.

In testimony whereof we hereunto set our hands, in the presence of two subscribing witnesses, this 14th day of November, 1881.

H. CLAY BASCOM.
FRANCIS RITCHIE.

Witnesses:

AUSTIN F. PARK,
JAMES T. GOODFELLOW.
